(57) **CLAIM**

The ornamental design for a delivery robot, as shown and described.

DESCRIPTION

FIG. 1 is a perspective view of a delivery robot embodying my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top plan view thereof; and,

FIG. 8 is an enlarged bottom plan view thereof.

The broken lines shown in the figures depict portions of the delivery robot that form no part of the claimed design.
